The corners 1, 2, 3 & 4, when matched from a spotted ground with an irregular border, Center A, consists of a group of leaves resting on a plain ground. Surrounding the center A, is the band B, on the outside edge of which are small bells and, on the inside edge the scalloped work, S, C, D, at the sides and E & F, at the end of the design when matched from to eight-pointed figures, in the centers of which are small sprigs and possettes.

The remaining portions of the design are occupied by the branch work 6.

The colors employed for the different portions of the design may be varied to suit the taste and wish of the manufacturer.
